UNITED STATES PATENT OFFICE.

ARMINTA E. WEBBEE, OF ROCHESTER, NEW YORK.

GLARE ELIMINATOR FOR HEADLIGHTS.

Application filed January 21, 1926. Serial No. 82,789.

My invention, in its broad aspect, has reference to improvements in devices for eliminating the objectionable rays thrown by the usual type of automobile headlights, and which give rise to the blinding glare noticeable when approaching a headlight of the usual type from directly in front. It has been found that the so-called "high rays" are the most objectionable since these pass directly into the tonneau of an approaching machine. My invention affords a complete screen for high rays, and other objectionable rays, and at the same time it does not so obstruct the headlight as to impair the desirable illuminating qualities which it is necessary for such a headlight to possess. Furthermore, my device may be mounted on any conventional form of headlight without changing its structure, and without employing skilled labor or unusual and complicated tools or implements. It may also be manufactured and sold at small cost, and may be replaced or repaired if broken or deranged, or adjusted to meet any reasonable requirements of practice.

Other and equally important advantages of my invention may be briefly defined as follows: first, my device is a metal stamping which may be manufactured in quantities by an ordinary metal stamping machine; second, the supporting elements of my device also constitute shade elements for eliminating high-rays; third, since my device is a sheet metal stamping it may be bent to different angles or adjusted with respect to the headlight to give different effects; and fourth, suitable means may be provided for preventing vibration and the like, such for instance, as lateral struts and these also may be integral or a part of the original sheet metal stamping.

The particular elements of my glare eliminator employed to accomplish the above and other equally important objects and advantages will be hereinafter more fully described in detail, and defined in the claim appended hereunto and forming a part of this specification.

In the accompanying drawings wherein is illustrated the preferred embodiments of my invention;

Figure 1 is a front view of a headlight provided with my shade,

Figure 2 is a side view of the same,

Figure 3 is a perspective view of my device per se, and

Figure 4 is a plan view of a modified form of my device and embodies lateral struts to prevent distortion or vibration.

In the drawings wherein like characters of reference designate like or similar parts throughout the several views:

(A) designates a conventional form of headlight having a body (B), a lens rim (C), and supporting elements (D).

My shade is an integral sheet-metal stamping having a circular, or otherwise shaped, body (1) which is preferably bent to present a concave face toward the headlight. Connected with the body by a web (2) are arms (3) which extend at an angle to each other and have therein slots (4) for receiving screws (5) for attaching the shade to the rim (C) of the headlight. The body (1) depends downwardly from the arms (3) and is ordinarily arranged as shown in Figures 1 and 2 to obstruct direct rays of the headlight, in which position the web (2) and arms (3) obstruct the objectionable high rays.

It will be noted that the arms (3) extend throughout a portion of their length angularly with respect to each other, and then relatively parallel as shown in Figure 3 so that by utilizing the slots (4) limited adjustment may be made of my device with respect to the rim of a headlight.

In Figure 4 is shown a modified form of my device in which lateral (and angularly disposed) arms (6) extend from the body (1) and these are adapted for attachment in any suitable manner to a headlight lens rim to form auxiliary supports or struts to prevent distortion or vibration.

In operation, my device is simply attached by screws (5) to the lens rim (C) of a headlight and the body bent to the desired position to effectively screen the undesirable rays while allowing the desirable rays to pass to properly illuminate the roadbed. In practice my device is placed upon the market with the arms extending substantially at right-angles to the body (or with the body depending) so that only minor adjustments need be made to adapt it to special circumstances.

While in the foregoing there has been illustrated and described such combination and arrangement of elements as constitute the preferred embodiment of my invention it is nevertheless desired to emphasize the fact that interpretation of the invention

should only be conclusive when made in the light of the subjoined claim.

Having described my invention and its objects with such attention to detail as will thoroughly acquaint one skilled in the art with its construction and advantages, I claim:—

A screen for vehicle headlights comprising a body adapted to be positioned in front of and over the central portion of a headlight lens and completely spaced therefrom to obstruct rays issuing from the central portion of the lens forwardly of the headlight and pass rays directed laterally of the vehicle toward the side of the road bed, said

body being substantially circular in plan and of less extent than the lens to pass light rays from the portions of the lens adjacent the edges thereof, and an extension on the top portion of the body of slightly less width than the diameter of the body and bifurcated to engage the rim of a headlight at two places to support the body and form a screen for obstructing high rays which would otherwise pass over and around the top edge of the body.

In testimony whereof, I affix my signature hereunto.

ARMINTA R. WEBBER.
